UNITED STATES PATENT OFFICE.

AMBROSE S. DOYLE, OF SHARON, MASSACHUSETTS.

MINE-FIELD PUZZLE.

1,297,451.

Specification of Letters Patent. Patented Mar. 18, 1919.

Application filed January 23, 1917. Serial No. 143,901.

To all whom it may concern:

Be it known that I, AMBROSE S. DOYLE, a citizen of the United States, residing at Sharon, in the county of Norfolk and State 5 of Massachusetts, have invented certain new and useful Improvements in Mine-Field Puzzles; and I do hereby declare the following to be a full, clear, and exact description of the invention, such as will enable others skilled 10 in the art to which it appertains to make and use the same.

This invention relates to a puzzle and has for one of its objects the provision of a device of this character, which is to represent 15 a body of water having mines therein and a harbor, and to solve the puzzle is to pass an obstacle representing a ship between the mines into the harbor without engaging the mines.

20 Another object of this invention is to provide a box or receptacle having a false bottom with a plurality of openings to represent the mines and a substantially U-shaped member at one end thereof to represent the 25 harbor, thus a ball or the like representing a ship is started rolling on the false bottom from the other end by inclining the box or receptacle in the hand to endeavor to place the ball in the harbor without falling in the 30 openings representing the mines.

A further object of this invention is the provision of a puzzle of the above stated 35 character, which shall be simple, durable and efficient, and which may be manufactured and sold at a comparatively low cost.

With these and other objects in view as will become more apparent as the description proceeds, the invention consists of certain novel features of construction, combination 40 and arrangement of parts as will be hereinafter more fully described and claimed.

For a complete understanding of my invention, reference is to be had to the following description and accompanying drawing, in which:

Figure 1 is a plan view of a puzzle, constructed in accordance with my invention,

50 Fig. 2 is a longitudinal sectional view of the same.

Referring in detail to the drawing, the numeral 1 indicates a substantially rectangular box or receptacle, the walls of which are to represent the banks or shore of a body

of water. A pair of spacing strips 2 are 55 located at each end of the box or receptacle 1 for supporting a false bottom 3 in spaced relation to the bottom of the box or receptacle 1 and is provided with a plurality of openings 4 to represent a plurality of mines. 60 The false bottom 3 represents the body of water. The openings 4 are arranged in staggered relation with each other making it more difficult to solve the puzzle, which will be hereinafter more fully described. 65

A substantially U-shaped member 5 is mounted upon the false bottom 3 which represents the body of water adjacent one end thereof and has its mouth or open end disposed adjacent one of the end walls. The 70 substantially U-shaped member 5 is to represent a harbor. A transverse strip 6 is secured to the false bottom 3 adjacent the opposite end from the harbor 5 and is to represent a wall. Between the strip 6 or the wall 75 and the end wall of the receptacle or box 1 is to represent a safety zone or starting point in which upon starting to solve the puzzle is positioned a ball or sphere 7 to represent a ship. The box or receptacle 1 is held within 80 the hand and by inclining the same in various angles, the ball representing the ship is rolled over the false bottom between the openings representing the mines until the ball has successfully passed into the harbor 85 or the substantially U-shaped member, thus solving the puzzle. If the ball happens to fall within one of the openings 4, by rules of the game, it is necessary to replace the ball at the starting point as falling into the 90 openings represents that the ship has been sunk by a mine.

While I have shown and described the preferred embodiment of my invention, it will be understood that minor changes in 95 construction, combination and arrangement of parts may be made without departing from the spirit and scope of the invention as claimed.

What is claimed is:

100 A puzzle or game comprising, a rectangular box, the side walls of said box representing the shores of a body of water; a false bottom arranged within said box and in spaced relation to the bottom of said box; 105 said false bottom having a plurality of apertures therein representing mines; a U-shaped member secured to the false bottom

and disposed adjacent one end wall of the box; said U-shaped member having its free ends directed toward the adjacent end wall; and a transverse strip secured to the false 5 bottom adjacent the opposite end wall of the box and adapted to form a safety zone to receive a ball.

In testimony whereof I affix my signature in presence of two witnesses.

AMBROSE S. DOYLE.
